(57) **CLAIM**

The ornamental design for a bowl-shaped light, as shown and described.

DESCRIPTION

The nature and intended use of the article in which the design is embodied is that of an electrically operated, bowl-shaped light that may provide different colors and shades of light to enhance the atmosphere of a gathering and the like.

FIG. 1 is a front elevational view of a bowl-shaped light showing my new design.

FIG. 2 is a perspective view thereof;

FIG. 3 is a right side view thereof; and,

FIG. 4 is a top view thereof.
